(73) Assignee: **LG ELECTRONICS INC.**, Seoul (KR)

Primary Examiner — Manpreet S Matharu

Assistant Examiner — Eliza Z Bennett-Hattan

(74) Attorney, Agent, or Firm — Birch, Stewart, Kolasch & Birch, LLP

(**) Term: **15 Years**

(21) Appl. No.: **35/501,793**

CLAIM

(22) Filed: **Apr. 25, 2016**

The ornamental design for a TV receiver, as shown and described.

(80) **Hague Agreement Data**

Int. Filing Date: **Apr. 25, 2016**
Int. Reg. No.: **DM/091558**
Int. Reg. Date: **Apr. 25, 2016**
Int. Reg. Pub. Date: **Oct. 28, 2016**

DESCRIPTION

(30) **Foreign Application Priority Data**

Oct. 30, 2015 (KR) 30-2015-0054891
(51) **LOC (11) Cl.** **14-04**
(52) **U.S. Cl.**
USPC **D14/126**
(58) **Field of Classification Search**
USPC D14/383, 385, 387, 421, 435, 126, 358
CPC H04N 5/64; H04N 2005/4408
See application file for complete search history.

1. TV receiver

1.1 : Perspective

1.2 : Front

1.3 : Back

1.4 : Left

1.5 : Right

1.6 : Top

1.7 : Bottom

1.8 : Enlarged

The evenly-spaced broken lines depict unclaimed portions of the TV receiver and form no part of the claimed design. The dash-dot broken lines of figures 1.4 and 1.8 are included to show partially enlarged views only and form no part of the claimed design.
